UNITED STATES PATENT OFFICE.

ALVAN P. GRANGER, OF DENVER, COLORADO.

ORE-SEPARATOR.

SPECIFICATION forming part of Letters Patent No. 269,848, dated January 2, 1883.

Application filed March 8, 1882. (No model.)

To all whom it may concern:

Be it known that I, ALVAN P. GRANGER, of the city of Denver, in the county of Arapahoe and State of Colorado, have invented certain new and useful Improvements in Ore-Separators; and I do hereby declare that the following is a full, clear, and exact description thereof, reference being had to the accompanying drawings, and to the letters of reference marked thereon, which form a part of this specification.

This invention relates to apparatus for dry-ore separation, and has for its object to achieve the largest practicable saving of mineral and at the same time to effect a very perfect separation of the mineral from the gangue.

To this end the invention consists in the features of construction and operation herein-after fully set forth, and pointed out in the claims.

Machines for dry-ore separation are constructed to operate by several dissimilar modes. By one class of machines the mass of mineral or mineral-bearing substance and gangue in crushed form is let fall into or through a current of air intended to be so adjusted as to carry off the gangue, which is relatively light, but to allow the mineral, which is relatively heavy, to fall through the current by its superior gravity. In another class of machines the mass is sustained upon a perforated plate or screen, upward through which a current of air is forced while the screen is being shaken, with a view to lift and bear away the lighter parts of the mass or gangue, and to leave the heavier parts or mineral. Both these classes of machines measurably fail to rescue certain valuable parts of the mineral, which, by reason of the flaky form of their particles or from other conditions, will be carried off by any air-current to which they may be exposed and which is strong enough to remove the gangue. In short, if the air-current be made strong enough to effect a practical separation, mineral is wasted, while, on the other hand, if the air-current be made weak enough to save this mineral it will be too weak to produce a satisfactory and practical separation. In the machines referred to the fault is that the mineral is exposed to the same air-current as the gangue and either loss of mineral or imperfect separation is, in the nature of the case, inevitable.

By the machine herein described only the

gangue is exposed to the air-current, which, obviously, to the extent that this is accomplished, insures, first, the removal of the gangue, and, 55 second, the retention of the mineral. For this purpose the mineral and the gangue are sustained upon an impreforate surface, and while thus sustained are agitated, so that the mineral or mineral-bearing substance or "base" by 60 its superior gravity settles to or toward the bottom of the mass, while the gangue or refuse by reason of its lesser gravity rises to the surface. Thus a sort of preliminary separation or stratification of the parts is first effected, after which the complete separation is produced by a superficial air-current which removes the gangue. This will be better understood by reference to the accompanying drawings.

Figure 1 is a side elevation of a machine shown to have three similar sections, of which, however, in a working-machine there are usually eight. Fig. 2 is a fragmentary longitudinal vertical section of the machine. Fig. 75 3 is a transverse vertical section through one of the precipitators. Fig. 4 is a top view. Fig. 5 is a top view of a fragment of one of the boards or plates upon which the mineral is agitated for the preliminary separation, mentioned and called the "precipitator." Fig. 6 is a vertical section of the precipitator.

A A' A² represent the frame of the machine.

B is a housing, which incloses the sides and the ends, B' being the converging bottom of 85 said housing in the form of a hopper running lengthwise of the machine.

C is a suction-fan connected by a flue, C', to take from the interior of the machine, and located at one end thereof.

D D D are the precipitators, arranged to form the top of the inclosure and in the inclined position shown.

E E E are hoppers arranged severally at the higher ends of the precipitators, for the 95 purpose of feeding material to be separated upon the precipitators.

F F F are adjustable wind-boards, covering the precipitators.

F' F' are side pieces, rising from the precipitators about in the planes of the lateral housing and laterally inclosing the space between the precipitators and wind-boards.

G is a shaft supported from arms A² of the

frame, and provided with eccentrics of small throw, from which, by the pitmen G' , the precipitators D are rapidly shaken.

H is a driving-shaft provided with suitable pulleys, by which and the connecting-belts C' and G^2 the fan C and shaft G are respectively driven.

I is a conveyer located in the trough-shaped bottom of the machine, for carrying off the gangue which settles therein after being drawn through the apertures d^2 .

J represents a tube or box, which may also be provided with a conveyer for the discharge of the separated mineral.

15 The machine will usually be surmounted by apparatus for sizing and drying the crushed ore preparatory to its being fed to the machine; but as such apparatus forms no part of the present invention, it is not here shown. It is sufficient to say that the several sections of the machine are adapted, as will be explained, for the separation of as many different "sizings" of crushed ore, and that any suitable means may be employed for the delivery of the proper 20 sizings to the several hoppers E .

25 The precipitators D are of peculiar construction. As here shown they are of wood, having relatively broad and shallow diagonal grooves or furrows d running in the directions indicated by dotted lines in Fig. 4, and intersecting each other to form intermediate diamond-shaped elevations, d' . Said grooves are preferably rounded out, or, in other words, are partly-cylindrical, as indicated in Figs. 5 and 6.

30 Except for a short distance from the hopper, the elevations d' are each provided with a hole, d^2 , extending through the board, and therefore giving communication with the interior of the machine, so that the fan C , when at work, will induce a current downward through each of said 35 holes, which are the only passages specially provided for its admission. The precipitators, being intended to be laterally shaken, are supported at each side by flexible metal strips D' , attached to the uprights A' of the frame, so as to work free of the housing B and of the side pieces, F' , though in proximity to both. At the upper end the precipitator is provided with the vertical metal flange d^4 , which, as seen in Fig. 40 45 50 55 60 65

sets up behind a depending metal strip, e , on the hopper to prevent "crush matter" from passing over the end of the precipitator. At its lower end the precipitator overhangs a spout, D^2 , which runs to a point, as shown in Fig. 3, and delivers through a pipe, J' , into the conveyer-box J , or otherwise, as may be desired.

The hopper E rests very close to the precipitator, as indicated in Fig. 2, allowing only such 60 65 70 75 80 85 90 95 100 105 110 115 120 125 130 135 140 145 150 155 160 165 170 175 180 185 190 195 mineral practically all preserved. It is particularly evident that the finer particles of mineral will have been saved, because, being smaller, they settle through the interstices of the larger particles of the same substance and are thereby shielded from the current, which near the foot of the precipitator may be strong enough to carry off coarse gangue of relatively high specific gravity. The removal of the superficial particles is of course facilitated by the greater motion imparted to them by the agitation of the precipitator, the lower portions of the mass being confined more or less by the superposed parts thereof.

15 The desired force of the air-current upward along the face of the precipitator is obtained by adjustment of the wind-board F—that is, by raising or lowering the free edge thereof, as stated. By making said board of glass the action upon the precipitator may be constantly or frequently observed, and the board raised or lowered, as required.

20 The diagonal courses of the furrows d , as shown, and by which the streams of crush are made to intersect, are found to be desirable in order to prevent the mass from packing, as it tends to do unless broken or interrupted.

25 It will be observed that the crush matter is strictly separated by agitation, whereby the superior gravity of the mineral may find opportunity to assert itself, and that the action of the air-current is subsequent to such separation, and is for the exclusive purpose of bearing away the so separated gangue. For practical purposes, however, the separation is not complete until the gangue is removed and the mineral or base obtained in a separate and distinct body. It will also be observed that the apertures d^2 are not in the surfaces 35 which uphold the crush matter, the latter being confined to the furrows d , which are imperforate.

30 The air-currents along the upper portions of the precipitator have been spoken of as less strong than those along the lower portions. It may not be necessary to explain that this is because the latter portions are nearer the point at which the air is admitted to the precipitator over the lower edge of the board F, and that the lower holes d^2 may therefore take the air to their full capacity, while the upper holes receive only such quantity as may be left for them.

35 While the precipitators have been described as of wood, they may, if preferred, be of metal; and, if of sheet metal, the elevations d' may be produced in the act of punching the holes d^2 .

In the general organization of the machine I do not restrict myself to the precise construction shown. The conveyers may, for example, be dispensed with. It is even practicable, probably, to dispense with the apertures d^2 in the precipitator by providing apertured tubes supported just above and near the surface of the precipitator, by which a current of air along its surface may be maintained; but, as at present advised, the construction shown is far preferable. So, also, the requisite agitation may probably be effected by means for stirring the mass of mineral and gangue on a plane imperforate and stationary surface, but manifestly with less advantage than by the method described.

I claim as my invention—

1. In a machine for separating dry-crushed ore, the precipitator D, provided with furrows d , and intermediate elevations, d' , having apertures d^2 , combined with suitable means for producing a current of air along the surface of the precipitator and downward through the holes d^2 , and with suitable means for shaking the precipitator, substantially as described.

2. In a machine for separating dry-crushed ores, the combination of the precipitator D, having imperforate furrows d , and intermediate apertured elevations, d' , a fan, C, and an adjustable deflecting board, F, together with suitable housing for confining and directing the air-current produced by the fan, substantially as and for the purposes set forth.

3. In a machine for separating dry-crushed ore, the combination of a vibrating, inclined precipitator, D, provided with intersecting furrows d and intervening elevations d' , having apertures d^2 , means for feeding the crush at the upper end of the precipitator into the grooves d , and means for producing currents of air upward over the surface of the precipitator and downward through the apertures d^2 , which currents are stronger through the lower apertures and weaker through the upper ones, whereby the lighter gangue first exposed on the surface of the crush, is first removed by the lighter air-current and the heavier gangue subsequently brought to the surface is afterward removed by the stronger currents, substantially as described.

In testimony that I claim the foregoing as my invention I affix my signature in presence of two witnesses.

ALVAN P. GRANGER.
